UNITED STATES PATENT OFFICE.

ROBERT E. PIERCE, OF ST. LOUIS, MISSOURI, AND FRED A. WELTS, OF BROOKLYN, NEW YORK, ASSIGNORS TO BEMIS BRO. BAG CO., OF ST. LOUIS, MISSOURI, A CORPORATION OF MISSOURI.

THREAD LOCK.

Application filed February 16, 1924, Serial No. 693,180. Renewed May 6, 1926.

Our invention relates to improvements in thread locks, and has for its primary object a thread lock which is operated intermittently and during certain periods of the movement of the needle bar so that the needle thread will be locked against feeding.

A further object is to construct a needle thread lock which is operated intermittently by the movement of the needle bar operating mechanism.

A still further object is to construct a needle thread lock which can be readily adjusted so as to accommodate various sizes of thread.

15 In the drawings,

Fig. 1 is a fragmental view of a sewing machine head with our device in position.

Fig. 2 is a fragmental top plan view of the same.

20 Fig. 3 is an enlarged section taken on the line 3—3 of Fig. 4 showing the tension and its operating mechanism in position.

Fig. 4 is an enlarged face view of our device with the tension mechanism removed.

25 Fig. 5 is a side view of a cross head employed.

Fig. 6 is a top plan view of same.

Fig. 7 is a view of the cross head stud.

30 Fig. 8 is a front elevation of the tightening member.

Fig. 9 is a fragmental view of a sewing machine head showing a modified form of thread lock.

35 Fig. 10 is a face view of modified form of tightening member.

Fig. 11 is a face view of the connecting link employed in the modified form, and

Fig. 12 is an edge view of the same.

In the construction of our device, we employ a sewing machine having a head 15. Mounted in this head is the usual needle bar 16. This needle bar is moved up and down by means of a lever 17. The lever 17 is preferably pivotally secured to the head 15 at a point indicated by the numeral 18. The lever 17 is rocked on the pivot 18 by means of a connection 19, which connection is secured to the driving mechanism (not shown) in the usual manner. The head 15 is provided with a pan tension 20 and with thread guides 21 and 22, while lever 17 is provided with a thread guide 23.

Mounted on the head 15 is a housing 24 which is provided with a circular opening

25. One side of the housing 24 is split as 55 at 26 so that same can be clamped down by means of the screw 27. Mounted in the circular opening 25 is the enlarged portion 28 of a stud. The enlarged portion 28 is equipped with a keyway 29 into which a pin 30 carried by the housing projects. This pin and keyway prevent the stud from turning in the housing but permits longitudinal movement therethrough. Formed integral with the housing 24 is a bracket 31 which is 60 provided with an opening 32 concentric with the opening 25 and into which the screw threaded end 33 of the stud passes.

Located on the screw threaded end 33 of the stud and between the housing 24 and 70 bracket 31 is a knurled thumb wheel 34, the purpose of which is to feed the stud backward and forward through the housing 24.

Formed integral with the enlargement 28 and on the opposite side of the screw 75 threaded portion 33 is a second threaded portion 35. This portion is provided with a multiple screw thread or helix so as to have a rather coarse lead. It will be noted from Fig. 3 that the helix does not extend 80 completely to the enlargement 28, leaving a cylindrical portion 36 and on this cylindrical portion is mounted a washer 37 which is provided with a central recess 38. Placed against the washer 37 is a pan tension 39. 85 Mounted on the helix is a tightening member 40, which is provided with internal grooves or screw threads to receive the threads formed on the projection 35. The tightening member has formed integral 90 therewith an arm 41, which is bifurcated on its end as indicated at 42. Each arm of the bifurcation is provided with a pad 43 which pad is for finishing purposes. Slidably located in the bifurcation 42 is a cross head 44, 95 which is provided with a central opening 45. This opening is adapted to receive the cylindrical portion 46 of the cross head stud. Adjacent to cylindrical portion 46 of the cross head stud is an integral collar 47 and 100 adjacent this collar is a screw thread portion 48, which is adapted to be extended through the lever 17 and secured thereto by means of the nut 49. This arrangement will allow the tightening member when rocked 105 by the lever 17 to travel backward and forward on the helix, and allow the cross head to slide on the cylindrical portion 46 with.

out imparting any twisting movement to the helix 35. In Fig. 9 we have shown a modified form in which the tightening member 40 is equipped with an integral extension 50 which is provided adjacent its free end with an opening 51. The free end of the extension 50 is placed within the bifurcation 52 of the connecting link 53. The bifurcation 52 is adapted to receive a pin 54 which extends completely therethrough and also through the opening 51, thus pivotally connecting the extension 50 and link 53. The lower end of the link is provided with an opening 55 which is adapted to be slipped over the cylindrical portion 56 of the cross head stud.

The operation of our device is as follows:

After the device has been assembled as in Figs. 1 and 9 the movement of the lever 17 oscillates the tightening member 40 on the helix, causing it to travel to and from the housing 24. This movement of the tightening member alternately presses the pans 39 towards each other and releases them periodically, thus exerting a locking and releasing action on the thread which passes between the tensions, this thread having been previously passed through the thread guide 21, the pan tension 20, the thread guides 22 and 23 and the intermittent tension or lock and so on to the needle. The degree of tension or locking imparted to the thread by our device is regulated in the following manner: The screw 27 is loosened and the thumb wheel 34 is rotated sliding the enlargement 28 backward or forward in the opening 25 of the housing. This backward or forward movement carries with it the tightening member and consequently allows either a greater or lesser degree of tension to be placed upon the thread between the pans 39 as desired or permits the insertion of a thicker thread and due to the fact that the stud is held against rotation by means of the keyway 29 and pin 30, the same amount of backward or forward movement as well as the period of time of such movements remains constant. This would not be the case were the stud permitted to turn in the housing because the position of the helix would then constantly change and consequently the effect of the tightening member be varied accordingly. After the proper adjustment has been made the screw 27 is tightened securely binding the enlargement 28.

The purpose of this binding is to prevent any accidental rotation of the thumb wheel 34 due to vibration of the machine. In the modification as shown the link 53 takes the place of the cross head and may be found desirable, under certain conditions. It being understood, of course, that we do not desire to limit ourselves to the precise con-

struction of the device as shown; because there are numerous machines on the market to which our device may be attached which operate the needle bar in a different manner than shown, but to which our device could be readily attached by the exercise of ordinary mechanical skill. Neither do we desire to limit ourselves to the number of threads shown on the helix as this number may be increased or decreased without departing from the spirit of our invention.

By our construction of thread lock the degree of pressure on the thread is maintained constant regardless of the speed at which the machine is run, because the lock is operated in both directions (pressure and release) by the driving mechanism of the needle bar and depends on no resilient means such as springs for any part of its movement. Furthermore, if a resilient means is used, for instance, to close the lock or exert pressure, the length of time during which the lock remains closed will vary in relation to the speed of the other moving parts of the machine, the lock remaining open a continually increasing length of time as the machine increases in speed, due to the inertia of the resilient means and the moving parts of the lock. In fact it would be possible to run a machine at such a high rate of speed that the lock would not close at all. This condition would be impossible in applicants' device because as aforementioned both movements of the lock are positively driven by the needle bar operating mechanism. Furthermore, if a resilient means is used it will crystallize in a short time and become useless, due to the rapidity of the expansion and contraction imparted to it.

Having fully described our invention, what we claim is:

1. A thread lock comprising in combination with a sewing machine head, its needle bar and needle bar operating mechanism, of a housing secured to said head, a stud slidably mounted in said housing, a helix formed on said stud, a pan tension mounted on said stud adjacent the housing, and means mounted on the helix and operated by the needle bar operating means for alternately exerting and releasing pressure at predetermined intervals on said pan tension, whereby a thread passing between the pan tension is alternately locked and released during the movement of the needle bar.

2. A thread lock comprising in combination with a sewing machine head, its needle bar and needle bar operating means of a housing secured to said head, a stud slidably mounted in said housing, means for slidably adjusting and projecting beyond said stud in said housing, a helix formed on said stud beyond the housing, pan tensions carried by said stud adjacent

the housing, a tightening member mounted on said helix, an arm formed integral with said tightening member, a stud carried by the needle bar operating means, said stud being operatively connected with the arm of the tightening member, whereby said tightening member is moved to and from said pan tension during the rocking of the needle bar operating means and means carried by the housing for securely locking the first-mentioned stud in adjusted position.

3. A thread lock comprising in combination with a sewing machine head having a needle bar and a needle bar operating mechanism, of a housing mounted on said head, a stud slidably mounted in said housing, means carried by said housing for preventing said stud from turning, means carried by the stud for adjusting the same laterally through said housing, means carried by the housing for locking the stud in adjusted position, a helix formed on the stud, a tightening member mounted on said helix, pan tensions carried by the stud between the tightening member and the housing, a bifurcated arm carried by said tightening member, a crosshead located in said bifurcation, and a stud carried by the needle bar operating mechanism, said stud extending through the crosshead whereby the tightening member is oscillated on the helix and moved to and from said pan tensions thus increasing and diminishing the tension at predetermined positions of the needle bar whereby a thread passing through said tension may be periodically held against movement therethrough.

4. A thread lock comprising a housing, a stud adjustably carried thereby, a helix formed on said stud, a tightening member mounted on said helix, said tightening member adapted to be rocked on said helix by the needle bar operating mechanism whereby the same is moved to and from said hous-

ing, and a pan tension mounted on the stud between the housing and tightening member, said pan tension adapted to be tightened and loosened alternately by movement of the tightening member on the helix.

5. A thread lock comprising a housing, a stud adjustably carried thereby, a helix formed on said stud, a tightening member mounted on said helix, pan tensions mounted on said stud between the tightening member and housing, said pan tensions adapted to be moved to and from each other when the tightening member is rocked on the helix, and means secured to the needle bar operating mechanism of a sewing machine for alternately operating the tightening member to and from the pan tension.

6. The thread lock of claim 4 in which the stud is provided with means whereby the same can be adjusted in the housing for regulating the pressure exerted by the pan tensions on the thread.

7. The thread lock of claim 5 in which the housing is provided with means whereby the stud can be locked in adjusted position.

8. A thread lock comprising a housing, a stud adjustably carried thereby, a helix formed on said stud, a tightening member mounted on said helix, pan tensions mounted on the stud between the housing and tightening member, and means carried by the tightening member and operated by the needle bar mechanism of a sewing machine whereby said tightening member may be rocked on said helix for moving the same to and from the housing and the pressure of the pan tensions on a thread be alternately increased and released thereby.

In testimony whereof, we have signed our names to this specification.
